UNITED STATES PATENT OFFICE.

THOMAS BOUCHER, OF MANCHESTER, NEW HAMPSHIRE, ASSIGNOR TO DRAPER COMPANY, OF HOPEDALE, MASSACHUSETTS, A CORPORATION OF MAINE.

LOOM-SHUTTLE.

1,171,766.

Specification of Letters Patent. Patented Feb. 15, 1916.

Application filed July 23, 1915. Serial No. 41,582.

To all whom it may concern:

Be it known that I, THOMAS BOUCHER, a citizen of the United States, and resident of Manchester, county of Hillsboro, State 5 of New Hampshire, have invented an Improvement in Loom-Shuttles, of which the following description, in connection with the accompanying drawing, is a specification, like characters on the drawing representing like parts.

This invention relates to improvements in loom shuttles for automatic filling replenishing looms of the type disclosed in prior Patents No. 906,748, granted Dec. 15, 1908, 15 and No. 1,092,959 granted April 14, 1914, which patents disclose means adapted to engage positioning faces upon the butts of the bobbins or other filling carriers and position the same properly as the bobbin is about 20 to be thrust into the shuttle jaws. The shuttles disclosed in these patents are particularly adapted to receive bobbins having longitudinal slots in their barrels adapted to receive the feeler when uncovered by the 25 unwinding of the filling and thereby to initiate the action of the transfer mechanism while there is a sufficient amount of filling upon the bobbin to complete the last pick across the loom before the bobbin is 30 discharged.

In the operation of the loom there is occasionally a failure of the hopper and shuttle to come into exact registry at the time of transfer, this being sometimes due to the 35 rebounding of the hopper as the same is advanced, and at other times by looseness occasioned by play between coöoperating parts of the loom, so that when the bobbin is thrust from the hopper toward the shuttle it 40 may strike upon the top of one of the guides for the base of the bobbin illustrated in the patents aforesaid in such a manner as to bend or break the same or to injure the bobbin, thus causing a smash in the loom.

In order to avoid the likelihood of such 45 accidents the present invention contemplates the mounting of the guides for the base of the bobbin in such a manner as to permit the slight floating of the guides, allowing a 50 wider range of action between the hopper and the shuttle jaws.

Another feature of the invention resides in providing a simplified construction which may be more readily assembled and more

easily repaired than in the devices heretofore 55 constructed.

Other objects of the invention will more fully appear from the following description and the accompanying drawings and will be pointed out in the annexed claims. 60

In the drawings which illustrate a preferred form of the invention, Figure 1 is a side elevation of a portion of a shuttle and a bobbin in the position in which it is about to be transferred from the hopper to the 65 shuttle jaws. Fig. 2 is a top plan view of the shuttle showing the bobbin in dotted lines as clasped within the shuttle jaws, Fig. 3 is a vertical longitudinal sectional view on lines 3—3 Fig. 2, and Fig. 4 is a 70 transverse sectional view on lines 4—4 Fig. 1, looking toward the left and showing a portion of the hopper which delivers the bobbins to the shuttle.

The body 1, of the shuttle is of the usual 75 construction having a chamber 2 for the reception of the bobbin and a lateral opening 3 through which the feeler may enter to feel upon the filling carrier within the shuttle. The filling carrier comprises a bobbin 80 4 having a series of rings 5 on its butt, oppositely disposed segmental portions being cut away to present parallel flat guiding faces 6 at right angles to the longitudinal plane of the feeler slot 7. 85

The bobbin or filling carrier is held in the shuttle by the usual grooved forked spring jaws 8, 9 which desirably are made integral and the portion 10 uniting the same embedded in the shuttle body. The bobbin is 90 guided into these jaws by a pair of flat reversely curved leaf springs 11—12 which are secured together or preferably made integral at one end and at the opposite end provided with upwardly projecting portions which are outwardly flared, the flared portion extending well above the plane of the top of the shuttle jaws. The upwardly projecting portions are provided with beveled or inclined surfaces which are adapted 100 to direct the butt of the bobbin into such position that as it is forced into the shuttle jaws the rings of the bobbin will be properly positioned in the grooves.

The guiding and positioning members are 105 placed within the jaws of the shuttle so that the integral or united ends thereof are seated in the crotch of the jaws 8, 9, and are

retained loosely in position by the metallic member or guide 13 for the base of the bobbin, the inclined portion 14 thereof engaging the upper edges of the leaf spring, 5 and a horizontal portion 15 forming a flat base for supporting said leaf springs. A top plate 17 of the form illustrated in Figs. 2 and 3 is provided to maintain the floating guides from tilting or vertical displacement. By reason of the fact that these resilient guides for the base of the bobbin are not rigidly secured in place a small amount of play is permitted so that the same may shift laterally to receive an improperly 10 presented incoming bobbin, such as illustrated in Fig. 4, which shows a bobbin being discharged from the hopper 18 and about to engage the guides in the shuttle. As the bobbin is thrust between these guides they 15 will be returned to their normal position, and by reason of their form and resilience will engage the flat faces of the butt of the bobbin and will rotate the same into proper angular relation to the jaws. The flared 20 ends of the guide form smooth cam surfaces for the engagement of the base of the bobbin and the resilience both to lateral and twisting strains causes the bobbin to be positioned between the jaws without injury to 25 the bobbin. The floating, or free lateral movement, permits a wider range of action for the guides than in the constructions disclosed in the prior patents and serves to 30 avoid smashes which may be occasioned by 35 the rebounding of the hopper or by the relative displacement of the hopper and shuttle as illustrated in dotted lines in the central portion of Fig. 4.

The fact that the spring guiding jaws 40 are not secured to the shuttle jaws by rivets or other securing devices avoids the weakening of the shuttle jaws so that the same are less likely to breakage, furthermore the construction is such that these spring guides 45 may be inserted in certain of the usual types of shuttles widely in use to adapt the shuttles for the reception of a bobbin having a feeler slot.

As described in my patents heretofore 50 mentioned, the use of a bobbin having the feeler slot is much more economical than the use of a bobbin provided with a feeling bunch, for the reason first that the slotted

bobbin avoids the necessity for using the excessive amount of filling necessary to produce the bunch for the feeler and second by the use of slotted bobbins the necessity for stripping the bobbin after its expulsion from the loom is avoided. It is therefore of great importance that the guiding means 55 for shuttles be of such a character that they can be introduced in the usual shuttles of automatic looms without material modification thereof when the looms are changed from the use of bobbins provided with feeling bunches to bobbins with feeler slots.

It is to be understood that the mechanism disclosed herein is illustrative merely of the invention and that the same may be embodied in other forms within the spirit and 60 scope of the following claims.

Having thus described my invention what I claim as new and desire to secure by Letters Patent is:

1. In a loom shuttle for bobbins having 75 butts provided with rings and with parallel guiding faces beyond said rings, a pair of spring jaws adapted to engage said bobbin rings, a pair of integral floating, resilient guides having upwardly extending outwardly flared ends projecting above said jaws adapted to engage the flat faces of the bobbin butts, rotate and direct the same between said jaws as the bobbin is thrust into the shuttle and means for retaining said 80 floating guide in the shuttle.

2. In a loom shuttle for bobbins having butts provided with rings and with parallel guiding faces, a pair of spring jaws to engage said bobbin rings, a floating guide 90 comprising a pair of integral longitudinally extending resilient members having upwardly extending inclined and flared ends projecting above said jaws, adapted to engage the flat faces of the bobbin butts and 95 rotarily direct the same into the bobbin jaws, said floating guides being retained in position by a guiding member for the base of the bobbins having an inclined portion engaging the upper edges of said guides and 100 a flat base portion forming a support for said guides.

In testimony whereof, I have signed my name to this specification.

THOMAS BOUCHER.
